TAPE JUMP-GAP DEVICE

Louis H. Morin, Bronx, N. Y.

Application October 11, 1947, Serial No. 779,289

17 Claims. (Cl. 18—30)

1

This invention relates to machines for producing separable fastener stringers where scoops or links are attached to the beaded edge of a tape in producing the stringers. More particularly, the invention deals with a device or mechanism on machines of the type and kind under consideration for providing a jump-gap on the tape in spacing stringer lengths, particularly at the point of juncture of tape ends and independent of normal spacing of stringer lengths on the tape.

The novel features of the invention will be best understood from the following description when taken together with the accompanying drawings, in which certain embodiments of the invention are disclosed and in which the separate parts are designated by suitable reference characters in each of the views, and in which:

Fig. 1 is a front view of a casting machine showing my improved mechanism or device, with part of the construction broken away and in section.

Fig. 2 is a section on the line 2—2 of Fig. 1.

Fig. 3 is a section on the broken line 3—3 of Fig. 2.

Fig. 4 is a partial section on the line 4—4 of Fig. 3.

Fig. 5 is a partial section on the line 5—5 of Fig. 4.

Fig. 6 is a sectional view on the line 6—6 of Fig. 2, on an enlarged scale, showing only part of the construction and with part of the structure broken away and in section.

Fig. 7 is an enlarged detailed view of part of the mechanism shown in Fig. 1, with parts broken away and in section.

Fig. 8 is a section on the line 8—8 of Fig. 7.

Fig. 9 is a partial section on the line 9—9 of Fig. 1, on an enlarged scale.

Fig. 10 is a side and sectional view of a tape feed control mechanism which I employ and indicating the method of its use.

Fig. 11 is a partial section on the line 11—11 of Fig. 10.

Fig. 12 is a diagrammatic view showing the various automatic controls for the tape feed and injection of casting material.

Fig. 13 is a plan view of a joined portion of tape forming the gap which is to be jumped in the operation of the machine; and

Fig. 14 is a section on the line 14—14 of Fig. 13.

In machines for forming separable fasteners, it has been a problem of stopping a casting machine when a tape end is reached, and of taking time to thread a new tape into and through the

2

machine to set it in a position preparatory to making another run of stringers on the new tape. It has also been experienced that upon examination of the tape, defects are found in the tape, which means that the tape would have comparatively short lengths. To cut out defects in the tape and to splice or otherwise join the tape ends for passage through the machine results in the jamming of the machine, and at times, would also result in destruction to tools used in the machine. Even if the splice went through the machine and scoop were cast on the spliced section, the stringers containing the spliced portion would not, of course, be saleable. In view of the fact that the splicing or joining of tape ends has not proved successful and satisfactory, it has been required to stop the operation of the machine for the re-threading operation, as stated above. It is also to be borne in mind that in some machines of the type and kind under consideration, one operator will take charge of several machines, and if a break or tape end occurs while the operator is engaged on another machine, the stopped machine will remain idle until such time that the operator can get to it to perform the necessary re-threading operation. Such delays materially interfere with, and reduce production capacity of the machine.

The re-threading operation and automatic stoppage of a machine when a tape end is reached, usually results in an extensive loss of tape lengths, and as a rule, anywhere from fifteen to twenty inches can be lost. Tape is an expensive part of the entire fastener and this loss would run into considerable money over a given run of any machine.

In overcoming the above, and other objectionable features to the present method of procedure, I provide a special gap splicing or coupling of tape ends, which is utilized as a control medium for controlling operation of the machine so that a definite and predetermined wide spacing or gap on joined tapes will be provided where each splicing or coupling occurs. With this method of procedure, it will be understood that tapes of different colors may be spliced or joined one to the other to provide continuous production of stringers on tape. Colors meeting certain specification requirements in daily production of any machine, and indefinite length of tapes of one or more colors can be constantly supplied to the machine so that an uninterrupted run of the machine is provided, thereby resulting in a maximum daily production and a minimum of tape wastage.

There is another detrimental feature in stopping fastener producing machines of the die casting type, and that is, if a machine is stopped for any length of time, the cooled dies would become overheated, which would result in production of improper castings, until the machine had been run sufficiently to acquire its normal balance temperature. Furthermore, from a standpoint of continuous operation, while in my new machine, during the gap stage of operation no casting material is injected into the dies, nevertheless, the machine continues to perform its normal function and while the location of the splice or gap section may result in a short or improper length zipper at one end, means is provided to start the casting operation on the tape after passage of the gap to produce a complete full zipper length on the new tape end.

In the accompanying drawings, the casting machine has been outlined in a more or less skeleton manner, simply to show the general adaptation of my invention to one type and kind of machine. In the present instance, a machine such as shown and described in my prior application Serial Number 574,697, filed January 26, 1945, now Patent No. 2,497,010 has been employed, and insofar as the valve actuating mechanism is concerned for controlling tape spacing, this valve mechanism is illustrated, in part, in my prior Patent 2,224,980 granted December 17, 1940.

The present device or apparatus may be said to comprise an attachment to fastener producing machines of any type or kind having means controlling attachment of fasteners to the tape by an electric switch mechanism actuated by the splice or gap in the tape to control the number of scoops applied to the tape before the gap is reached. Then to continue feed of the tape through the machine in passage of the gap by the scoop attaching means, such for example, as a pair of dies, and to then set the mechanism of the machine so as to begin the attachment of a full and complete stringer length immediately after the gap section of the tape has been passed, or as promptly thereafter as is practical, so as to minimize the action of tape loss. Here it is to be kept in mind that each stringer has a predetermined tape end beyond the end scoops for attachment and finish of the stringer in mounting on respective supports.

Considering Fig. 1 of the drawing, I have here indicated and outlined, the upper framework 15 of a die casting machine, employed for die casting scoops or links directly upon the beaded edge of a stringer tape. In the upper side portions of the framework are similar air cylinders 16-16', operating plunger rods 17-17'. The rods 17-17', carry at their inner ends, scoop or link forming dies 18-18' which are movable toward and from each other, and a tape 19 in forming separable fastener stringers in manners known in the art. At 20 I have shown the drive shaft of the machine driven from a suitable electric motor, not shown, through a pulley and belt drive, as indicated at 21. At 22 is shown a hand-wheel for rotating the shaft, and at one end of the shaft is a gear 23 meshing with a gear 24 at one end of a rotatable valve 25 and also with a gear 26 on a shaft 27.

Considering Figs. 2 and 3 of the drawing, it will appear that a housing 28 is mounted on the frame, this housing being shown to the right of Fig. 1 of the drawing. The shaft 27 is mounted in suitable bearings in the housing 28 and se-

cured to the shaft within the housing is a worm 29. Supported in the upper part of the housing 28, and at right angles to the shaft 27, is another shaft 30. Freely rotatable on the shaft 30 is a clutch 31 supported by a flanged sleeve portion 32 to which is keyed a worm wheel 33 meshing with the worm 29. It will thus be seen that the clutch 31 is constantly driven while the shaft 30 remains stationary. It is preferred that the ratio between the shaft 27 and rotation of the shaft 30 through the medium of the worm and worm gear will be such that the shaft 27 as well as the shaft 20 make thirty revolutions to each single revolution of the shaft 30, when the clutch is brought into operative engagement to drive the clutch disc 34 keyed to the shaft 30, as indicated at 35.

A trip dog 36, note Fig. 3, is normally held, by a spring 37 operating upon a lug 38 on the dog, in engagement with a pivoted catch 39 on the wheel 34. The dog 36 carries at its upper end a link or arm 40 pivotally coupled with a solenoid 41 actuated by a micro-switch, later described. Actuation of the solenoid 41 will move the dog into position releasing it from the catch 39, allowing the clutch 31 to then drive the disc 34 for one complete revolution, at the termination of which, the dog will again move into engagement with the catch 39, stopping rotation of the shaft 30.

Mounted at one end of the housing 28 and around the shaft 30 is a plate 42 having a port or passage 43 opening through the face of the plate, as seen at 44, and with which a pipe or tube 45 also communicates. Mounted on a square end 46 of the shaft 30 beyond the plate 42 is a rotatable member or disc 47. At one surface of the disc is a circumferentially long recess 48, note Fig. 6, having a port communicating therewith through the other surface of the disc, as seen at 49. Attached to the plate 42 is a cap 50 with which an air supply pipe 51 communicates. This pipe supplies air under pressure to the port 49 for admission to the annular groove 48 for discharging air from the pipe 45 to the gooseneck mechanism 52 of the casting machine, diagrammatically shown in part, in Fig. 12 of the drawing. The groove or recess 48 is sufficiently long to allow for a predetermined number of cycles of operation of the machine. For example, twenty-four cycles, whereas between the grooves is a blank or shut-off section 53, clearly seen in Fig. 6, which accommodates four cycles of operation of the machine, sufficient to accommodate the skip of the splicing of the tape, plus an added two cycles to accommodate the ratio of thirty to one revolution of the respective shafts.

A spring 54 is mounted on a pin portion 55 of the disc 47 to normally support said disc upon the face of the plate 42 to affect a substantial seal between the disc and plate, particularly when the section 53 is in registration with the port opening 44. Secured to a conical end 56 of the shaft 30, protruding beyond the housing 28, is a cam 57 actuating a plunger valve 58 controlling transmission of air to a cylinder 59, as diagrammatically seen in Fig. 12. The cylinder 59 is shown in detail in Fig. 10, the cylinder having a piston 60 therein actuating a long rod 61, carrying at its upper end a spring actuated finger or pawl 62 and adapted to operate the control chain 63, as later described. At 64 is shown the pipe for admitting air to the lower end of the cylinder 59 and at 65 is shown the pipe for admitting air to the upper end of the cylinder. The pipes

64 and 65 also act as exhausts and in the diagrammatic showing in Fig. 12, the cam 57 is shown in its inoperative position with the valve 58 depressed so as to exhaust air from the pipe 64 while admitting air to the pipe 65 through the compressed air supply, as at 66. It will appear that when the valve 58 is raised by the cam, air will be exhausted from the pipe 65, and air under pressure admitted to the pipe 64 to raise the piston 66 for the purposes later stated. As the operation of the valve 58 is clear from the illustration in Fig. 12, no further detailed description will be given.

Considering now Figs. 3, 4 and 5, it will appear that the catch 39 has a clevis pin 67 for pivotal mounting in the disc 34, the pin being held in the normal inoperative position shown in Fig. 5 by the dog 36. The spring actuated plunger 68 mounted in the disc 34 is adapted to move the clevis pin 67 into position operatively engaging the internal teeth 31' of the clutch 31 when the dog 36 is moved outwardly to release the catch 39. It will appear that the disc 34 has an eccentric portion 69 on which the dog 36 operates. The catch 39 projects at the eccentric portion for engagement with the dog, as will be clearly apparent from a consideration of Fig. 3 of the drawing.

It will appear, from a consideration of Figs. 1, 10, 11 and 12, that the rotatable valve 25 is mounted in a suitable casing or cylinder 70 supported in the housing 71, the housing having a supplemental dual valve cylinder 72, shown in part, in Fig. 10, and diagrammatically in Fig. 12 of the drawing. This construction is the same as shown more in detail in the application above identified, as well as in the patent previously granted to applicant. For this reason, no extensive detailed description will be given, except in stating that the valve 25 has numerous ports or passages which are indicated in part, in Fig. 1, controlling transmission of air to various mechanisms of the machine. In Fig. 12 of the drawing I have indicated the valve 25, diagrammatically, with an air pipe 73 leading therefrom to the valve cylinder 72. It will be understood that the valve 25 controls the timing of air supply in the operation of the machine for transmission of air to the gooseneck, diagrammatically shown at 52, in Fig. 12 of the drawing, for producing successive casting shots in forming groups of links or scoops on the beaded edge of the stringer as clearly taught in the application above referred to.

In the valve cylinder 72 are two valves 74—75 actuated by cams 76—77, respectively. The cams 76 and 77 are shown on the shaft 78 of the valve 25, in Fig. 1 of the drawing. The valve 74 controls the normal tape spacing between stringer lengths and operates to shut off supply of air to the valve 75 so that no air will be supplied to the gooseneck during the normal tape spacing. In the diagrammatic showing of Fig. 12, the valve 74 has its port 79 in position to supply air to the valve 75 through the by-pass 79'. However, the valve 75 is shown in closed position, but when actuated by the cam 77, air will be supplied to the pipe 51, then through the disc 47, and thus to the pipe 45 leading to the gooseneck 52. It will be understood that the disc 47 is normally maintained in an open-port position for free transmission of air therethrough.

Pivoted to the cylinder 72 is a spring actuated pawl or dog 80, note Fig. 10, which normally seats in a recess 81 in the valve 74, as diagrammati-

cally seen in Fig. 12 of the drawing to maintain the valve 74 at all times in its open position and unaffected by the cam 76. Pivoted to the pawl 80 is a link 82 also pivoted to a spring pressed finger 83 which operates upon the chain 63, as well as spaced pairs of trip blocks 84 on said chain. In Fig. 10 of the drawing, one of the blocks 84 is shown supporting the finger 83 outwardly to maintain the pawl 80 in an inoperative position, allowing the cam 76 to move the valve 74 into closed position. These pairs of blocks 84, in other words, control the normal spacing of the tape in defining stringer lengths. The finger in riding on the chain 63 between the blocks keeps the pawl 80, at all times, in the locked or operative position, thus maintaining the valve 74 in open position.

The chain 63 is constantly driven from a worm 35 on the shaft 78 operating a worm gear 86 on the shaft 87. A chain driving sprocket 88 is fixed to the shaft 87 outwardly of a supplemental housing 88' secured to the housing 71. The chain 63 also passes around another sprocket 89 adjustably supported in an elongated slotted part 90 of the frame, this construction being employed to adapt the machine for chains of different lengths and with different spacing of the blocks 84 on the chain in controlling different stringer lengths. It will appear from a consideration of Fig. 10 that part of the chain passes over a plate 91 which serves as a backing to support the chain, particularly in movement by the finger 82 to quickly advance the chain. This operation is performed immediately after the gap has been passed through the machine, or through the dies, so as to advance a pair of the blocks 84, regardless of the position they may assume at such time, to the position shown in Fig. 10, so as to start the next casting operation on the tape to form a complete stringer length.

Now turning to Fig. 13, here is shown, diagrammatically, the gap portion 92 or splicing in the tape. At 93 is shown the last or part of the last scoops formed on the tape before approaching the splicing 92, and at 94 is shown part of the first scoops applied to the tape after the gap or splicing has passed. The scoops 94 start at a predetermined distance from the splicing, as shown by the space 95 to provide the usual end on the tape for attachment of the stringer to a suitable support. In other words, in bringing the two blocks 84 to the position shown in Fig. 10, the pawl 80 will be held out of engagement with the valve 74 for two cycles of operation of the machine, sufficient to produce the spacing 95, whereupon the pawl 80 will be returned to normal operative position, allowing the air to pass to the gooseneck for discharge of casting material into the die impressions.

It will be understood that the tape has a normal feed through mechanism forming no part of the present invention to feed the tape consistent with the length of group castings formed on the tape so that one group of castings is spaced properly with respect to the next group in forming the complete stringer length of a multiplicity of such groups. For example, in the application heretofore mentioned, six scoops are simultaneously formed on the stringer at one time, thus the tape is moved sufficient to receive the next group of six castings.

Considering Fig. 9 of the drawing, it will be seen that the tape 19 passes down through a fixed guide 96 and a movable guide 97 secured to a pivoted arms 98, note Fig. 1. Mounted in a suit-

able bracket 99 is a spring actuated plunger 100, which bears against the arm 98 to tensionally support the movable guide 97 in engagement with the tape. The yieldable guide adapts the splicing 92 for free passage into and through the machine, while at the same time, applies sufficient tension to the tape to maintain the same in any fed position, as will be apparent. The tape enters the machine from a reel or spool, not shown, and first passes through an electric feeler or trip mechanism 101, indicated in Fig. 1, and shown in detail in Figs. 7 and 8. This mechanism comprises a suitable casing 102 in which are supported two micro-switches 103 and 104, the switch arms of which are shown at 105 and 106.

Supported in the casing are switch actuating pins 107 and 108, the pin 107 being offset with the pin 108, in other words, inwardly as viewed in Fig. 7, or to the right as viewed in Fig. 8, for alinement with correspondingly off-set rollers 109 and 110. The roller 109 is positioned to register with an elongated opening 111 formed in the splice 92 of the tape, whereas the roller 110 is adapted to engage the tape at one side of the opening 111, thus the roller 110 controls stopping of the machine when a tape end is reached. Whereas the roller 109 passes through the opening 111 to actuate the pin 107 and the switch 103 as and when the jump-gap actuation of the machine is desired.

The casing 102 has a block 112 supported thereon in which the pins 107 and 108 operate. The upper end of the block has recesses, as at 113 and 114 to receive the rollers 109 and 110 in actuating said pins, as will be apparent. The upper surface of the block 112 is grooved to receive the beaded edge of the tape, as seen at 115, note Fig. 8, so as to maintain alinement of the tape through the control mechanism. The tape is further guided by another grooved block 116 carried by a slide 117. The slide 117 has a tongue and groove coupling with a back supporting plate 118. The front face of the slide has two recesses 119 and 120 in which spring actuated plungers 121 and 122 are mounted, the plungers carrying or supporting the rollers 109 and 110. The plungers are held in place by a plate 123 which carries a fingerpiece 124 by means of which the slide may be manually raised, particularly in the operation of threading a tape through the machine. The upper end of the supporting plate 118 carries an angle-piece 125 extending over the slide 117 to form a backing for a spring 126 which normally depresses the slide to hold the tape guide 116 in position. Each plunger 121 and 122 has an extending lip, one of which is shown at 127, in Fig. 8 of the drawing, and this lip is engaged by the slide 117 in raising the rollers 109 and 110 out of engagement with the tape. The slide 117 has a forwardly extending flange 128 forming a seat for springs 129 and 130 which support the rollers 109 and 110 in engagement with the tape.

From the foregoing, it will be apparent that as long as the normal tape is passing through the electric feeler or trip mechanism 101, the machine will continue to function in its normal manner, forming the stringer lengths at spaced intervals along the tape. However, when the splice or gap section 92 approaches the mechanism 101, the roller 109 will move downwardly through the aperture 111, causing said roller to actuate the pin 107, which in turn will actuate the micro-switch 103.

Turning now to Fig. 12, here is diagrammatical-

ly shown an electric circuit comprising two supply lines 131 and 132 controlling the circuit to an electric motor 133 for actuating the machine. It will appear from Fig. 12 of the drawing that the switch 103 is normally open and is closed by the actuation of the pin 107 to complete the circuit to the motor 133 and to the solenoid 41, which is diagrammatically shown in this figure. It will also be apparent that the switch 104 is normally closed, completing the circuit to the electric motor 133 and to an electric control valve 134 for supply of air, under pressure, through the pipe 135 to the valve mechanism 25. However, when the pin 108 is actuated, the circuit is broken and the motor is stopped and supply of air is shut off to the valve 25. This latter switch may also control other mechanisms of the machine, as will be apparent. From the foregoing, it will appear that in the jump-gap spacing of the tape, the machine continues to perform its function and that air to the gooseneck through the pipe 135 is shut off by the control disc 47 for the distance of the blocking section 53, which is sufficient to prevent the formation of castings from the point of forming the last castings, as at 93 to the formation of the next castings, as at 94, in Fig. 13 of the drawing. In this connection it will be understood that the spacing of the electric feeler or trip mechanism 101 with respect to the dies 18-18' will be such as to start the cycle of operation of the disc 47, which is actuated through the clutch 31. After this mechanism has been put into operation, it will perform its single revolution through the clutch, which results in the continuation of the forming of castings on the tape for twenty-four machine operations until the splicing 92, is about to enter the dies. At this moment, the section 53 blocks off the supply of air to the gooseneck and the tape continues its feed for four operations of the machine when the splicing 92 passes through the dies. Then for two cycles of machine operation the trip blocks 84 shut off supply of air to the pipe 51, as above described, whereupon the pawl 86 is moved into its operative position. At the same time, the dog 36 stops rotation of the clutch 31 and the normal cycles of operation of the machine in forming castings on the stringer will continue.

Considering Fig. 11 of the drawing, it will appear that the shaft 87 is coupled with the sprocket 88 through a spring actuated clutch collar 136 having a ratchet engagement with a disc 137. The collar 136 is keyed to the shaft and normally held in engagement with the disc to provide for the drive. However, at any time, the chain 63 may be manually adjusted to a starting position by simply pulling downward at the right side of the chain, as seen in Fig. 10, or on the other hand, this ratchet engagement also provides for the free feed of the chain by the finger 62, as above stated, it being understood that the drive between the shaft 87 and the shaft 78 is through the worm drive, which necessitates the free ratcheting of the sprocket 88 in the manner described.

To briefly summarize the operation of the machine, let us assume that the machine is performing its normal function of casting groups of scoops on the tape edge forming the stringer lengths intermittently spaced through the actuation of the valve 74. Then let us assume that a splice, as at 92, approaches the feeler and trip mechanism 101. The instant the roller 109 drops

through the aperture 111, the switch 103 is operated, which actuates the solenoid 41, moving the dog 36 into inoperative position or out of engagement with the catch 39. The spring pressed plunger 68 then moves the clevis pin 67 in position to be engaged by one of the teeth 31' of the clutch 31, causing the shaft 30 to then immediately starts its rotation, thus rotating the disc 47 and the cam 57. Castings will continue to be formed on the tape as the operation of the machine continues, until the machine has completed twenty-four cycles of operation, forming twenty-four groups of castings on the tape, at which time, the section 53 of the disc 47 will block air passage to the pipe 45, shutting-off supply of air to the gooseneck, resulting in the failure of formation of castings on the tape as the tape continues its normal feed through the machine for four cycles of operation. At that instant, the cam 57 has moved the valve 58 in position to admit air, under pressure, to the pipe 64 to raise the piston or plunger 60, actuating the finger 62 to advance a pair of control blocks 84 to the position shown in Fig. 10. Then for two cycles of operation air is still shut off to the gooseneck through the valve 74, after which the dog 36 again engages the catch 39, stopping rotation of the shaft 30 and the machine then continues to perform its normal function and will produce on the new section of the tape a complete and full stringer length. The actuation of the switch 104, as above stated, upon reaching a tape end simply stops completely the operation of the machine as the circuit to the motor is shut off and all other mechanisms of the machine are brought at rest.

Immediately after the finger 62 has completed its operation of advancing a pair of blocks 84, the cam 57 will release the valve 58 to automatically return the piston to the lower end of the cylinder and to correspondingly lower the finger 62 by reversing the charge of air into the cylinder 59, as will be apparent.

Summarizing the invention, it will be seen to comprise apparatus for continuously casting die cast bodies on a mounting member containing a spliced section in which are provided casting means for casting said bodies on the mounting member, means for continuously feeding the mounting member thereto, means in the form of the roller 109 for detecting said spliced section in advance of its introduction to the casting means, switch means responsive to said detecting means, limiting means (as shown in Figs. 2-6) actuatable by said switch means for limiting the number of die cast bodies cast on the mounting member throughout an interval during which said spliced section approaches the casting means, said limiting means serving to render said casting means inoperative while the spliced section is advancing therethrough, and means for inactivating said limiting means. Adjusting means in the form of the blocks 84 and the mechanism which operates them are also provided, said means being responsive to said switch means and more particularly to said limiting means for delaying the operation of the casting means for a predetermined interval after the spliced section has passed said casting means.

The blocks 84, and both the mechanism which operates them and which is operated by them, in effect, constitute valve means actuatable by the limiting means prior to inactivation of the latter for stopping the air supply to the casting means for a predetermined interval after the spliced

section has advanced through the casting means.

It will be apparent that my invention, generally speaking, provides automatic means for controlling wide or gap spacing of members as applied to a tape or other mounting member for purposes of the type and kind stated, where other means may be employed for providing normal or fixed spacing of the members or devices thereon. In the present disclosure, the members or devices are in the form of die cast scoops or links for producing a predetermined article of manufacture. Other types of castings may be similarly applied and spaced, on a mounting member, particularly where it is desirable to splice or otherwise join the mounting member at intervals for the purpose of providing a continued uninterrupted machine operation. It is also to be understood that the same principles can be applied to any type and kind of machine where devices or members of any type or kind can be formed in any desired manner and attached to a mounting.

Having fully described my invention, what I claim as new and desire to secure by Letters Patent is:

1. In a machine for forming separable fastener stringers, means for applying scoops to the edge of a stringer tape having a spliced portion to form stringer lengths longitudinally of the tape, means for spacing the stringer lengths on each side of said spliced portion, said spacing means comprising a trip mechanism on the machine in predetermined spaced relationship with respect to the scoop applying means, means for advancing the tape through said mechanism, means responsive to said mechanism for inactivating said scoop applying means, said mechanism being actuatable by the passage therethrough of said spliced portion to inactivate said scoop applying means through said last-named means and thus to space the stringer lengths on opposite sides of said spliced portion.

2. In a machine for forming separable fastener stringers, means for applying scoops to the edge of a stringer tape having a spliced portion to form stringer lengths longitudinally of the tape, means for spacing the stringer lengths on each side of said spliced portion, said spacing means comprising a trip mechanism on the machine in predetermined spaced relationship with respect to the scoop applying means, means for advancing the tape through said mechanism, said scoop applying means being responsive to said mechanism and said mechanism being actuatable by the passage therethrough of said spliced portion to inactivate said scoop applying means and thus to space the stringer lengths on opposite sides of said spliced portion.

3. In a machine for forming separable fastener stringers, means for guiding a tape into and through the machine, means for applying scoops to an edge of the tape and for intermittently spacing the tape to form stringer lengths longitudinally of the tape, the tape having spliced portions spaced longitudinally thereof, and means comprising a trip mechanism disposed in the path of movement of said tape through the machine and in predetermined spaced relation with respect to said scoop applying means for automatically stopping attachments of scoops to the spliced part of the tape as the spliced part passes through the scoop attaching means.

4. In a machine for forming separable fastener stringers, means for guiding a tape into and through the machine, air-actuated means for ap-

plying scoops to an edge of the tape and for intermittently spacing the tape to form stringer lengths longitudinally of the tape, the tape having at least one spliced portion longitudinally thereof, means comprising a trip mechanism disposed in the path of movement of said tape through the machine and in predetermined spaced relation with respect to said scoop applying means for detecting the spliced part of the tape as the spliced part approaches the scoop attaching means, and means comprising an air control and blocking disc actuated by said trip mechanism and disposed in the path of transmission of air to the scoop applying means for controlling the number of scoop applying operations performed by the machine before reaching the splice in the tape end for stopping the attachment of scoops while the splice is passing through the scoop applying means.

5. In a machine for forming separable fastener stringers, means for guiding a tape into and through the machine, air-actuated means for applying scoops to an edge of the tape and for intermittently spacing the tape to form stringer lengths longitudinally of the tape, the tape having spliced portions spaced longitudinally thereof, means comprising a trip mechanism disposed in the path of movement of said tape through the machine and in predetermined spaced relation with respect to said scoop applying means for automatically stopping attachments of scoops to be spliced part of the tape as the spliced part passes through the scoop attaching means, said last named means also comprising an air control and blocking disc actuated by said trip mechanism and disposed in the path of transmission of air to the scoop applying means controlling, in a predetermined cycle ratio with respect to cycle operations of the machine, the number of scoop applying operations performed by the machine before reaching the splice in the tape and the number of cycles of machine operations during which attachment of scoops is blocked in passing the splice in said tape, and means actuated by said trip mechanism for controlling the start of attachment of scoops to the tape beyond the splice.

6. In a die casting machine for forming separable fastener stringers, the combination of dies for forming fastener scoops on one edge of a tape, means for guiding said tape through the machine for positioning with respect to said dies, means comprising an air actuated gooseneck for injecting casting material into the dies to form the scoops on the tape, and automatically actuated means for spacing one length of scoops from a next succeeding length, said automatically actuated means comprising automatically actuated valves for controlling supply of air to the gooseneck, and means disposed in the path of movement of the tape through the machine for actuating said valves to shut off the supply of air to the gooseneck.

7. In a machine for applying devices to and longitudinally of an elongated mounting and for periodically spacing one length of devices from a next succeeding length, means for guiding the mounting through the machine, means for applying devices on the mounting, and means operatively engaging the mounting in predetermined spaced relationship with respect to said device applying means for automatically controlling operation of the device applying means to stop the application of devices to the mounting during predetermined cycles of operation of the

machine in order to form said spaced lengths of devices.

8. In a machine for applying devices to and longitudinally of an elongated mounting and for periodically spacing one length of devices from a next succeeding length, means for guiding the mounting through the machine, means for applying devices on the mounting, means operatively engaging the mounting in predetermined spaced relationship with respect to said device applying means for automatically controlling operation of the device applying means to stop the application of devices to the mounting, and automatically actuated means for controlling the re-application of devices to the mounting.

9. In machines for applying devices to an elongated mounting and for periodically spacing devices on the mounting, means for guiding the mounting through the machine, means for applying devices on the mounting, switch means for momentarily rendering said device applying means inoperative, and means engageable by the mounting for actuating said switch means.

10. In machines for applying devices to an elongated mounting and for periodically spacing devices on the mounting, means for guiding the mounting through the machine, means for applying devices on the mounting, switch means for momentarily rendering said device applying means inoperative, and means engageable by the mounting for actuating said switch means, said last-named means comprising a switch actuating element normally supported in inoperative position by said mounting.

11. In machines for attaching devices to an elongated mounting having at least two predetermined sections, means for applying devices to the mounting, switch means actuatable to render said device applying means inoperative, means traversable by the mounting in advance of the means for applying devices thereto, said latter means being engageable with the mounting and serving to detect one of said predetermined sections and coincidentally therewith to actuate said switch means.

12. In machines for attaching devices to an elongated mounting having two predetermined sections, means for applying devices to the mounting, switch means actuatable to render said device applying means inoperative, a trip and feeler mechanism through which the mounting passes in advance of the means for applying devices thereto, said mechanism being engageable with the mounting and serving to detect one of said predetermined sections and coincidentally therewith to actuate said switch means, and said mechanism including means for stopping operation of the machine when a mounting end passes through said mechanism.

13. In machines for attaching devices to an elongated mounting having two predetermined sections, means for applying devices to the mounting, switch means actuatable to render said device applying means inoperative, a trip and feeler mechanism through which the mounting passes in advance of the means for applying devices thereto, said mechanism comprising a spring-pressed roller engageable and supportable by the mounting and releasable at one of said sections, and a switch-actuating pin operable by the roller when the latter is released from the mounting.

14. Apparatus for continuously casting die cast bodies on a mounting member containing a spliced section comprising casting means for casting said bodies on the mounting member, means

13

for continuously feeding the mounting member thereto, means for detecting said spliced section in advance of its introduction to the casting means, switch means responsive to said detecting means, limiting means actuatable by said switch means for limiting the number of die cast bodies cast on the mounting member throughout an interval during which said spliced section approaches the casting means, said limiting means serving to render said casting means inoperative while the spliced section is advancing therethrough, means for inactivating said limiting means, and adjusting means responsive to said switch means for delaying the operation of the casting means for a predetermined interval after the spliced section has passed said casting means.

15. Apparatus for continuously casting die cast bodies on a mounting member containing a spliced section comprising casting means for casting said bodies on the mounting member, means for continuously feeding the mounting member thereto, means for detecting said spliced section in advance of its introduction to the casting means, switch means responsive to said detecting means, limiting means actuatable by said switch means for limiting the number of die cast bodies cast on the mounting member throughout an interval during which said spliced section approaches the casting means, said limiting means serving to render said casting means inoperative while the spliced section is advancing therethrough, and means for inactivating said limiting means.

16. Apparatus for continuously casting separable fastener elements on a tape containing a spliced section comprising: air-actuated casting means for casting said elements on the tape, means for continuously feeding the tape thereto, means engageable with the tape for detecting said spliced section in advance of its introduction to the casting means, means responsive to said tape-engaging means and actuated thereby when a spliced section is detected, rotatable limiting means operable by said responsive means, said rotatable limiting means being disposed in the path of air supply to said casting means and being adapted to pass air to the casting means to enable a limited number of fastener elements to be cast on the tape throughout an interval of rotation during which said spliced section approaches the casting means and thereafter through another interval of rotation to close the air supply to the casting means and thus pre-

14

5 vent the casting of elements on the tape while the spliced section is advancing through the casting means, means associated with said rotatable limiting means for inactivating the latter after the spliced section of the tape has passed through the casting means, and valve means actuatable by the rotatable limiting means prior to the inactivation of the latter for stopping the air supply to the casting means for a predetermined interval after the spliced section has advanced through said casting means.

17. Apparatus for continuously casting separable fastener elements on a tape containing a spliced section comprising air-actuated casting means for casting said elements on the tape, means for continuously feeding the tape thereto, roller means engageable with the tape for detecting said spliced section in advance of its introduction to the casting means, switch means responsive to said roller means and actuated thereby when a spliced section is detected, limiting means operable by said switch means, said limiting means having associated therewith a rotatable member disposed in the path of air supply to said casting means, said rotatable member being adapted throughout a portion of its rotation to pass air to the casting means to enable a limited number of fastener elements to be cast on the tape while said spliced section approaches the casting means and thereafter throughout another portion of its rotation to close the air supply to the casting means and thus prevent the casting of elements on the tape while the spliced section is advancing through the casting means, means associated with said limiting means for inactivating the latter after the spliced section of the tape has passed through the casting means, and valve means actuatable by said limiting means prior to the inactivation of the latter for stopping the air supply to the casting means for a predetermined interval after the spliced section has advanced through said casting means.
